UNITED STATES PATENT OFFICE

163,544

MOTOR VEHICLE

James R. Selzer, Fort Wayne, Ind., assignor to
International Harvester Company, a corpora-
tion of New Jersey

Application April 11, 1950, Serial No. 9,128

Term of patent 14 years

(Cl. D14—3)

To all whom it may concern:

Be it known that I, James R. Selzer, a citizen of the United States, residing at Fort Wayne, in the county of Allen, and State of Indiana, have invented a new, original, and ornamental Design for a Motor Vehicle, of which the following is a specification, reference being had to the accompanying drawings, forming part thereof, in which:

Figure 1 is a side elevational view taken from one side of a motor vehicle showing my new design. It is to be understood that the side elevational view of the opposite side of the motor vehicle while not shown is substantially the same as shown in Figure 1.

Figure 2 is a perspective view;

Figure 3 is a front elevational view; and
Figure 4 is a rear elevational view.

I claim:

The ornamental design for a motor vehicle as shown and described.

JAMES R. SELZER.
